UNITED STATES PATENT OFFICE.

HERMAN C. PRIEBE, OF BLUE ISLAND, ILLINOIS.

TRUCK FRAME.

Application filed September 14, 1926. Serial No. 135,889.

My invention relates to railway car tracks and particularly to the side frames thereof.

The invention has for one of its objects an improved assembly between the arch bars of the side frames and the bolster columns or guides. In carrying out this object of my invention, the bolster columns have reduced ends to form pins and seats at the bases of the pins, these pins entering openings 5 formed in the arch bars, these arch bars engaging said seats. The bolster columns are desirably also riveted to the arch bars that are entered by the pins and the assembly of these arch bars and the bolster columns is 10 further assured by expanding the outer ends of the pins into heads that lap these arch bars. In the preferred embodiment of the invention, each side frame has two bolster columns which are joined at their lower ends 15 by a yoke which is assembled with one of the arch bars, the ends of the columns opposite said yoke being formed with the pins that enter the other arch bar, the latter arch bar being riveted to said columns adjacent said 20 pins.

In accordance with another feature of the invention, an assembling member is employed to join the bolster column uniting yoke with one of the arch bars. This assembling member surrounds this arch bar and has a portion passing through said yoke. Said assembling member is desirably inclusive of a U-shaped part that receives the yoke and the arch bar adjacent the yoke and a bolt passing through the yoke and the sides 35 of said U-shaped part.

Another feature of my invention relates to the journal boxes assembled with the arch bars. In accordance with this feature of the 40 invention, the ends of the arch bars meet upon the tops of the journal boxes which are bolted to the arch bars and a pin is driven into one arch bar end at each end of the side frame, the other arch bar ends having holes 45 in which said pins are received. The bolts which assemble the journal boxes with the arch bars are thus relieved of shearing strains, that otherwise might be effectively exerted by the arch bars.

50 I will explain my invention more fully by reference to the accompanying drawing in which Fig. 1 is a side view of a car truck employing a side frame of my invention, parts being shown in section; Fig. 2 is a sectional plan view on line 2—2 of Fig. 1; Fig. 55 3 is a vertical sectional view of a part of the

structure appearing in Fig. 1; Fig. 4 is a view on line 4—4 of Fig. 3; and Fig. 5 is a view, from beneath, illustrating some of the parts in the region of the bolster column 60 joining yoke, parts being broken away.

The truck side frame illustrated includes an upper arch bar or compression member 1, a lower arch bar or tension member 2, bolster columns 3 and 4, a yoke 5 joining the lower 65 ends of the bolster columns, journal boxes 6 at the ends of the side frame, and tie links 7 which assemble the lower ends of the journal boxes with the yoke 5. The arch bars 1 and 2 are desirably of rolled steel converging 70 toward the ends of the side frame and whose ends are brought together above the journal boxes. These journal boxes are assembled with the arch bars by means of the U bolts 8 whose side portions pass upwardly 75 through the journal boxes and whose base portions are clamped against the bottoms of the journal boxes by means of the nuts 9 screwed upon the ends of the U bolts. The inner upright sides of said U bolts pass 80 through the tie links 7 and engage the outer ends of these links. The inner ends of these links are received within recesses 10 that are formed in the bottom side of the yoke 5 near the middle of the yoke. The tie links thus 85 serve to prevent the bottoms of the journal boxes from spreading apart.

The yoke 5 is assembled with the arch bar 2 by means of an assembling member which is inclusive of a U shaped part 11 that receives said yoke and arch bar and a bolt 12 which passes through said yoke and the sides of the part 11. This assembling member thus surrounds the arch bar and has a portion, the bolt 12, which passes through 90 said yoke. The upper ends of the bolster columns 3 and 4 are reduced to form pins 13 and seats at the base ends of these pins. These pins enter openings formed in the upper arch bar 1, this arch bar engaging the 95 aforesaid seats. The pins have their upper or outer ends expanded into heads that lap the arch bar 1, as illustrated most clearly in Fig. 1. The bolster columns desirably have wing portions 14 extending therefrom toward 100 the ends of the side frame, rivets 15 passing through these wing portions and the arch bar 1 further to assure the assembly of this arch bar with the bolster columns.

105 A pin 16 is driven into one arch bar end at each end of the side frame, preferably the

lower arch bar end, the other arch bar ends having holes in which said pins are received in the process of assembling the ends of the arch bars. These pins serve to guard the 5 bolts 8 from shearing action of the arch bars. These pins are shaped to slip into said holes to permit separation of the arch bars.

Changes may be made without departing from the invention.

10 Having thus described my invention, I claim:

1. A truck side frame including upper and lower arch bars; two columns between said arch bars, there being a yoke joining 15 similar ends of said columns and assembled with one of said arch bars, the ends of the columns opposite said yoke being reduced to form pins and seats at the bases of the pins, said pins entering openings formed in 20 the other arch bar and which arch bar engages said seats, said pins having their outer ends expanded into heads that lap this arch bar; and rivets also uniting said columns and the latter arch bar.

25 2. A truck side frame including upper and lower arch bars; and two columns between said arch bars, there being a yoke joining similar ends of said columns and assembled with one of said arch bars, the 30 ends of the columns opposite said yoke being reduced to form pins and seats at the bases of the pins, said pins entering openings formed in the other arch bar and which arch bar engages said seats, said pins having their outer ends expanded into heads that lap this arch bar.

3. A truck side frame including upper and lower arch bars; and two columns between said arch bars, there being a yoke 40 joining similar ends of said columns and assembled with one of said arch bars, the ends of the columns opposite said yoke being reduced to form pins and seats at the bases of the pins, said pins entering openings formed in the other arch bar and which arch bar engages said seats.

4. A truck side frame including upper and lower arch bars; two columns between 50 said arch bars, there being a yoke joining similar ends of said columns and assembled with one of said arch bars, the ends of the columns opposite said yoke being reduced to form pins and seats at the bases of the pins,

said pins entering openings formed in the other arch bar and which arch bar engages 55 said seats; and rivets also uniting said columns and the latter arch bar.

5. A truck side frame including upper and lower arch bars; a column between said arch bars and having one end reduced to 60 form a pin and a seat at the base end of said pin, the pin entering an opening formed in one of the arch bars, this bar engaging said seat, the outer end of said pin being expanded into a head that laps this arch bar; and a rivet also uniting said column and the latter arch bar.

6. A truck side frame including upper and lower arch bars; and a column between 65 said arch bars and having one end reduced to form a pin and a seat at the base end of said pin, the pin entering an opening formed in one of the arch bars, this bar engaging said seat, the outer end of said pin being expanded into a head that laps this 70 arch bar.

7. A truck side frame including upper and lower arch bars; two columns between 75 said arch bars, there being a yoke joining similar ends of said columns; and an assembling member surrounding the arch bar that is adjacent said yoke and having a portion passing through the yoke.

8. A truck side frame including upper and lower arch bars; two columns between 80 said arch bars, there being a yoke joining similar ends of said columns; a U shaped member receiving said yoke and the arch bar adjacent the yoke; and a bolt passing 90 through said yoke and the sides of said member.

9. A truck side frame including upper and lower arch bars; journal boxes at the 95 ends of the side frame and upon the tops of which the ends of said arch bars meet; bolts passing through the ends of the arch bars and assembling said journal boxes therewith; and a pin driven into one arch bar end at each end of the side frame, the other arch bar ends having holes in which said 100 pins are received, said pins being shaped to slip into said holes.

In witness whereof, I hereunto subscribe my name.

HERMAN C. PRIEBE.
